UNITED STATES PATENT OFFICE.

ARTHUR BERNARD ROLFE-MARTIN, OF KENTISH TOWN, LONDON, ENGLAND, ASSIGNOR
TO PERISCOPIC PRISM COMPANY, LIMITED, OF KENTISH TOWN, ENGLAND.

TELESCOPE-SIGHT ATTACHMENT.

1,198,665.

Specification of Letters Patent. Patented Sept. 19, 1916.

Application filed February 23, 1916. Serial No. 79,906.

To all whom it may concern:

Be it known that I, ARTHUR BERNARD ROLFE-MARTIN, a subject of the King of Great Britain, residing at 28 Prince of Wales Crescent, Kentish Town, in the county of London, England, have invented certain new and useful Improvements in Telescope-Sight Attachments, of which the following is a specification.

10 This invention relates to methods of attachment of telescope sights to firearms and more particularly to such methods as rely on the inter-engagement of dovetail members for such attachment, the chief object of the 15 present invention being to provide an improved dovetail fitment whereby a telescope sight can be more readily and reliably attached to rifles and like firearms while permitting of ready removal and replacement. 20 According to the present invention the telescope tube carries a single member provided with a parallel dovetail part adapted to enter into engagement with a corresponding parallel dovetail part carried on the 25 firearm and to be securely held when so engaged by means of a fixed stop or plate provided, for instance, on the forward end of the firearm dovetail part, and a nose on a 30 spring catch which automatically operates at the position of abutment against said stop or plate to prevent displacement away from the same.

In the preferred construction a female parallel dovetail member may be attached 35 to the bolt casing of the rifle by screws or other suitable means, the dovetail being closed at its forward (muzzle) end to provide a stop for a male parallel dovetail member carried by the telescope tube. A spring, 40 which may be sunk in and along one face of the female dovetail, carries a stop at the rear end which the male dovetail depresses as it slides over it when the telescope is inserted into position and which is released 45 and engages with the rear end of the male dovetail when the telescope is fully up to the front stop. A suitable device such as a second spring sunk in either dovetail may be provided to press the telescope attachment firmly against a face or faces of the female dovetail, insuring that the telescope shall always occupy exactly the same position during the process of taking aim.

In order that the said invention may be 50 clearly understood and readily carried into

effect, I will describe the same more fully with reference to the accompanying drawings, in which:

Figure 1 shows in elevation a telescope sight secured in place upon a rifle. Fig. 2 is a cross section on the line $x-x$ of Fig. 1, through the sight mounting and bolt casing of the rifle; and Figs. 3 and 4 show in elevation the two dovetail members.

A is the telescope tube, of which the outline only is indicated, as it forms no part of the present invention.

B is the rifle stock.

C is the bolt casing.

D is the female dovetail member fitted upon the bolt casing and E is the male dovetail member firmly secured on the tube A.

The female member D must be fitted upon the rifle with great accuracy, so that the telescope tube may lie parallel to the axis of the rifle barrel. For this purpose the side of the bolt casing may have two longitudinal surfaces c, c' carefully machined flat to receive two corresponding surfaces on the back of the member D. The face of the front wall c^2 of the bolt casing may also be machined at the side against which the end plate d of the member D abuts to give a proper abutment for the member, which is preferably secured at the lower flange d' only, by the screws d^2 entering the side of the bolt casing. These screws pass through the bolt casing and the ends projecting into the bolt chamber are filed off accurately flush with and conforming to the radius of the inside face of said chamber.

Part of the male member E is formed as a slotted sleeve e which embraces and can be fixed to the telescope tube A immediately in front of the fixed collar a shrunk on the tube and serving to prevent any forward displacement of the telescope due to the recoil of the rifle on firing.

The two dovetail members must fit with great accuracy and to prevent the male dovetail riding backward when it has been slid into position the member D is provided with a spring catch d^3 lying in a recess d^4 in the bottom of the dovetail, the end of the spring carrying a projecting stop d^5 which springs up behind the rear end of the member E when the latter has been pushed in until its front end meets the end plate d closing the front of the female dovetail.

To prevent any looseness one side of the

male dovetail is recessed to receive the spring e' which lies along its face and presses against the inner face of the female dovetail, but this spring does not form the 5 actual dovetail face, which is constituted by the narrow solid face or ledge e^2 above the spring channel.

It is of great importance that the shock of firing shall not displace the sight and the 10 shock of recoil must therefore be transmitted to the telescope tube in a manner which avoids any displacement. This is effected in the present fitting by securing the member D so that its front plate d abuts firmly 15 against the front wall c^2 of the bolt casing C and by securing the male dovetail so that its front end abuts against the plate d . Also to take the shock as near as possible to the 20 base of the dovetail the front end of the male dovetail may be slightly recessed as shown in Fig. 4 to leave a nose e^3 at the base projecting to meet the plate d . The shock is therefore transmitted through the plate d , male dovetail member, sleeve e and collar a and at no point is there danger of 25 bending or distortion of the parts.

What I claim and desire to secure by Letters Patent of the United States is:—

1. A telescope sight attachment for firearms comprising a single parallel dovetail member on the telescope tube, a corresponding parallel dovetail member on the firearm, a fixed stop on the second member determining the position of the telescope member 30 and means for securing the latter member at the position of abutment against the said stop.

2. A telescope sight attachment for firearms comprising a single parallel dovetail member on the telescope tube, a corresponding parallel dovetail member on the firearm, a fixed stop determining the position of the telescope and a spring catch having a nose which engages a dovetail member at the 45 position of abutment against the stop.

3. A telescope sight attachment for firearms comprising a single member on the telescope tube provided with a parallel male dovetail part, a corresponding parallel female dovetail member on the firearm, a plate closing the forward end of the female dovetail and means for holding the male dovetail in position in abutment with the 50 said plate.

55 4. A telescope sight attachment for firearms comprising a single parallel dovetail member on the telescope tube, a correspond-

ing parallel dovetail member on the firearm, a fixed stop determining the position of the telescope, and a spring catch fitted to a face 60 of the dovetail member on the firearm and having a nose which engages the end of the telescope dovetail member when the latter is in abutment against the stop.

5. A telescope sight attachment for firearms comprising a single parallel dovetail member on the telescope tube, a corresponding parallel dovetail member on the firearm, a fixed stop determining the position of the telescope and a spring catch fixed in a recess 70 in the base of the female dovetail member and adapted to be depressed by the male dovetail member on entry of the latter into the female dovetail and to be released automatically at the position of abutment 75 against the stop so as to engage the male dovetail member.

6. In a telescope sight attachment for rifles, a dovetail member having a flange at one side, a machined face formed on the bolt 80 casing of the rifle, on which face the side flange of the said dovetail member is screwed and a corresponding dovetail member on the telescope.

7. A telescope sight attachment for firearms comprising coöperating parallel male and female dovetail members on the telescope and firearm, a plate closing the end of the female dovetail and a projecting nose on the end of the male dovetail adapted to 90 abut against the said plate.

8. A telescope sight attachment for firearms comprising coöperating parallel male and female dovetail members on the telescope and firearm, one of the dovetail faces 95 being formed with a shallow recess leaving part of the face at the side uncut, and a spring fitted in the said recess and adapted to bear against the face of the second dovetail member while the dovetail fit is made 100 by the said uncut part of the face.

9. A telescope sight attachment for firearms comprising a single parallel dovetail member on the telescope tube, a corresponding parallel dovetail member on the firearm, a fixed stop determining the position of the telescope, means for securing the latter at the position of abutment against the said stop, a parallel slotted sleeve on the first 105 dovetail member embracing and fixed to the telescope tube and a collar fixed on the said tube as an abutment for the said sleeve.

ARTHUR BERNARD ROLFE-MARTIN.
